UNITED STATES PATENT OFFICE.

CHAS. HENRY HUDSON, OF 17 ASKE TERRACE, COUNTY OF MIDDLESEX,
ENGLAND.

IMPROVEMENT IN TRANSFERABLE EMBROIDERY-PATTERNS.

Specification forming part of Letters Patent No. 41,776, dated March 1, 1864.

To all whom it may concern:

Be it known that I, CHARLES HENRY HUDSON, of 17 Aske Terrace, in the county of Middlesex and Kingdom of Great Britain, have invented a new and Improved Transferable Pattern for Embroidery, Braiding, &c.; and I do hereby declare that the following is a full, clear, and exact description of the same.

This invention consists of a paper or fabric which has its surface printed with ornamental embroidery-patterns in such a manner that when said printed paper is dampened and pressed upon any cloth or other surface the said ornamental embroidery-patterns will be transferred.

In printing the original patterns upon paper I use block-patterns—that is, patterns formed by inserting strips of metal into wood, or formed by any other material. The ink which I use is composed of about equal parts of sugar and gum-arabic mixed with any color and dissolved in water to the consistence of cream, so that it readily adheres to the edges of the block-patterns, and that it leaves an impression on paper or other material upon which said block-pattern may be pressed down. After the original patterns on paper have thus been prepared, the muslin or fabric upon which

the pattern is to be transferred is dampened and stretched upon a table or flat surface, and the original pattern is placed on it, face down, and pressed lightly with a towel or cloth all over. By these means the patterns are transferred upon the muslin or fabric ready for embroiderying, braiding, stitching, &c.

Instead of dampening the muslin or other fabric upon which the pattern is to be transferred, said fabric may be simply stretched and the original pattern placed on it face down, and after dampening the back of the latter the pattern can be transferred by treating with a towel or cloth, as above described.

If desired, the original pattern can be made with two or more colors, and the copies will also show said colors, which in some cases is of great advantage.

Having thus described my invention, I claim, and desire to secure by Letters Patent, as an improved article of manufacture—

A paper or fabric which has its surface provided with a transferable embroidery-pattern, as herein described.

CHARLES HENRY HUDSON.
